MIXING ATTACHMENT

Abram I. Podell, New York, N.Y.

Application July 22, 1947, Serial No. 762,625

3 Claims. (Cl. 74—191)

1

This invention relates generally to the field of mixing and more particularly to a novel mixing attachment.

In many fields of industrial endeavor it is necessary in the course of manufacturing procedures to mix liquids with liquids of varying viscosities or to mix liquids with solids of varying densities and physical properties. Various stirring and/or tumbling methods are used requiring intricate and complicated machines. Many industries, however, require the mixing of ingredients which have been placed in tanks or vats and where the operation is not consistently repetitive so that it is necessary and desirable to utilize so-called mixing attachments which are portable and may be transferred from one tank, vat or open drum to another.

Since the vessels or vats with which the present class of devices are used, vary considerably in size and depth, it has been necessary to utilize shafts of different lengths to support the propeller. These have been connected by double collars or sleeves utilizing set screws or the like. Such constructions have the disadvantages of requiring a number of different shaft lengths and of producing a structure which is frequently difficult to clean after the mixing operation is over. The set screws oftentimes cut the metal of the shaft so that splinters or shavings drop into the material being mixed. Furthermore, such construction is disadvantageous in that at high speed a state of imbalance occurs with a consequent vibration of the device during operation. Such a vibration tends to increase the noise of operation, tends to increase the wear of the running parts and frequently causes the clamping mechanism which secures the device to the edge of the vat, to loosen.

It is therefore one of the principal objects of the present invention to provide a mixing attachment of the class described in which by reason of the novel organization and inter-relation of the various elements thereof, relatively light clamping structures are needed to positively secure the mixing attachment to the tank and to relatively permanently secure the same in any adjusted position thereof.

Another one of the objects of the present invention lies in the provision for releasably clamping a relatively long propeller shaft so that a single shaft may be utilized in connection with mixing in vessels of widely varying depth.

A still further object herein lies in the provision of structure of the class described wherein the propeller shaft is securely clamped or

5 gripped during operation, and yet when it is desired to substitute a new shaft or alter the position of the shaft, this may be quickly and conveniently accomplished.

10 A very important consideration with mixing attachments of the present class lies in the cost thereof. The average user of this class of device has use for a large number of them and the lower the cost thereof the more of them he may have in service with the same capital investment. By far the greater proportion of the materials which are mixed by this class of device are of a relatively heavy nature and most efficient mixing is obtained when this is done at low speed. In order to promote flexibility and easy shifting from one job to another, it is desirable that the attachments be operated by electric motors. As is well known in the present art, low speed electric motors are relatively more expensive than high speed motors. This fact has been taken into consideration in the design of prior art mixers and the speed of the mixing element has been reduced by the use of gear trains. This construction is both noisy and expensive and requires care with regard to lubrication. In accordance with the present invention desired reduced speed of the mixing element is obtained by the use of a cone friction transmission so that the speed may be adjusted even while the device is in operation.

20 25 30 35 In accordance with the present invention provision is made for proper covering of the sheave-belt construction so that it is protected from dirt and also from accidental contact with the operator thereby providing an important safety feature.

The importance of proper mixing speed cannot be over-emphasized in connection with the efficient use of devices of the class described. Depending, of course, upon the viscosity and other characteristics of the materials being mixed, it has been found that the higher the speed of rotation of the mixing element or impeller, the slower the actual speed of mixing, as the mixing element or elements tend to push the material being mixed out to the edge of the tank where said material is spun around forming a vortex or pocket giving an illusion of mixing, but with a relatively reduced amount of actual mixing taking place. Tests were made by placing a pair of electrodes in the upper part of a tank and connected by wires to electric measuring instruments. The tank was filled with pure water to a level equal to the level of said electrodes. Pure water is a relatively poor conductor

of electricity. In the bottom of the tank there was submerged a bag of salt (sodium chloride). As the mixing proceeds the salt enters into solution with the water, thereby permitting an increased flow of electricity in the circuit with the measuring instruments. Tests were made at different speeds and it was found that substantially 150 R. P. M. of the propeller or mixing element gave the best mixing speed. It was found that it actually took longer to mix at a higher speed than at a lower speed because at the higher speed certain materials do not have sufficient time to flow into the propellers for mixing. With the slower speed of rotation the mixing element actually beats the material which flows into the spaces between the blades.

High speed mixing is not only usually unsatisfactory for the reasons just described, but there is also an increase in cost to the user because the horse-power required to drive the mixing element increases substantially in the ratio of the cube of the increase in speed. Thus, doubling the diameter of a propeller increases its effective area four times. For example, assuming a five-inch propeller having an effective area of twenty-five square inches, when the diameter is increased to ten inches, the effective area increases to one hundred square inches. It would thus appear that increasing the effective area of the propeller would result in an increase of four times the amount of liquid mixed at the same speed of rotation of the propeller. With an increase in the diameter of the propeller the power requirement, however, is increased to the ratio of

[New H. P.]
[Old H. P.]

Thus, for example, if the five-inch propeller mentioned above required a one-quarter horse power motor to rotate the same under a given load at a given speed, it would require thirty-two times the old H. P. or eight horse-power to drive the ten-inch propeller at the same speed. In accordance with the present construction the mixing speed is where possible and where dictated by the nature of the ingredients being mixed maintained at substantially 150 R. P. M. This enables the use of relatively large propellers or mixing elements with a relatively small motor. Better mixing is thus obtained at lower power cost.

Another object herein lies in the provision of a device of the class described which by reason of the proper balancing and arrangement of the parts permits the same to be secured to tanks or vessels of relatively light construction without additionally reinforcing the edge thereof which supports the mixing attachment.

The underslung and offset position of the motor removes it from the path of fumes from the mixture which might have a harmful effect.

Another object of the present invention lies in the provision of simple means for the declutching of the transmission so that the power to the main drive shaft or propeller shaft may be disconnected. This permits the motor to continue operating without breaking the electrical circuit thereto. Thus, the electrical switch for the motor may be substantially removed from the location of the device and brushless motors which are relatively lower in cost, may be used instead of explosion-proof motors.

These objects and other incidental ends and advantages will more fully appear in the progress

of this disclosure and be pointed out in the appended claims.

In the drawings in which similar reference characters designate corresponding parts throughout the several views:

Figure 1 is an enlarged vertical sectional view, partly in elevation, as seen from the plane 1-1 on Figure 3.

Figure 2 is a fragmentary enlarged vertical sectional view of an alternate form of chuck.

Figure 3 is a plan view of a first embodiment of the invention.

Figure 4 is an end elevational view of the first embodiment of the invention.

Figure 5 is a fragmentary vertical sectional view, partly in elevation, of a second embodiment of the invention.

Turning now to the first embodiment of the invention illustrated in Figures 1 to 4 inclusive, the device generally represented by reference character 10 includes broadly: a relatively stationary frame 11; a relatively movable frame 12; a prime mover 13; speed changing and power transmission means 14; a guard element 15; a main shaft 17; a mixing element shaft 18; a mixing element 19; and declutching means 20.

The relatively stationary frame 11 includes a body 21 having a laterally extending arm 22 terminating in a threaded member 23. The member 23 is penetrated by a screw clamp 24 having an operating handle 25 and an inner terminal 26 which is adapted to clamp against the inner wall of a vessel or container (not shown), the outer wall of said container being thus compressed against the surface 27 of the frame 11. The lower end of the frame 11 is provided with transversely arranged orifice penetrated by a pin 28 which serves to pivotally mount the movable frame 12. The pin 28, at each end thereof may be provided with a washer 29 and means for preventing disconnection such as a cotter pin 30.

The movable frame 12 includes a body 31, generally vertically arranged, which is provided at the lower rear edge thereof with a mounting plate 32. The mounting plate 32 serves as a base to which the mounting bracket 33 of the motor 13 may be connected as by means of a nut and bolt 34. The top wall 35 of the movable frame 12 above the body 21 is substantially coextensive in width with the guard element 15 (see Fig. 3) and is provided with four tapped orifices 36. Threadedly engaged with and projecting laterally from the upper portion of the movable frame 12 is a clamping bolt 51 which projects through an elongated slot 52 in the stationary frame 11 and is provided with a wing nut 56. The forward portion 37 of the movable frame 12 has an upstanding rim and serves as a base for securing the auxiliary frame element 38. The base 37 is provided with a countersunk bore 40 for passage of the main shaft 17.

The prime mover 13 may be in the form of any suitable electric motor being in proportional correlation with the rest of the device. The motor 13 is secured on the mounting plate 33. The motor may have the usual shaft 53 and a pulley 54 secured thereto.

The auxiliary frame member 38 comprises a side wall 41, a top wall 42 and a bottom wall 43. Mounted by means of a forced fit and located centrally in the top wall of the frame member 38 is a bearing 44. The forward portion of the top wall 42 has an indentation 45 and downwardly projecting from the rear portion of the top wall are a pair of ears 46 (only one being

seen in Fig. 1). The bottom wall of the auxiliary frame 38 has a bearing 47 axially aligned with the bearing 44, a boss in the form of a cylindrically raised portion 48 provided with a bearing seat 49 therein and disposed within the bottom wall 43 are the tapped orifices 50.

The main shaft, indicated generally by reference character 17, has longitudinally arranged keyways 55 and has its upper end 57 and its lower end 58 reduced in diameter.

The speed changing and power transmission means 14 includes a conical driving member 67 having an integral shaft 17 which is journaled in a shaft bearing 68. The bearing 68 has an ear portion 70 with a substantially horizontal arm portion 71. The shaft 17 has an enlarged portion 14, and fixed thereon, a suitable pulley 75 to receive the driving belt 76. Contacting the driving member 67 is a slideable collar or annular driven member 84 which is actuated by the fork member 86. The fork member 86 engages an annular groove in member 84 and is adjustable to move upwardly or downwardly on the adjusting screw 87 to correspondingly shift the member 84.

The guard element 15 includes a handle 60, a top wall 61 angularly disposed with respect to the main body of the guard element, a recessed portion 62 in the front part of the top wall, a front wall 63 and a bottom outwardly extending flange 65. The guard element is secured to the movable frame by any suitable means such as the screws 82 which engage the orifices 36.

The declutching means, indicated generally by reference character 20, comprises a knurled head adjusting screw 72 having a lower terminal 80. The mixing element shaft 18 has secured thereto, the mixing element 19 which may be a propeller of the desired pitch and size to insure optimum mixing effect.

The mixing element shaft holding means 16 comprises a knurled collar 90 fixed on shaft 17, a tightening collar 91, a collet 92, and a locking collar 9.

Assembly of the device is a relatively simple matter. With the motor 13 mounted on the plate 33, it may be secured to the mounting plate 32 of the movable frame. The movable frame is attached to the stationary frame and is held in position by the pin 28 which is locked in place by the washer 29 and cotter pin 30. The bearing 47 is forced into the frame element 38, followed by the main shaft 17 and member 84. The bearing 44 is then forced into position. Attachment of the power transmission means 14 is proceeded with and held in place by the pin 69. The adjusting screw 87 may now be turned through the fork member 86 until the bottom end rests in the seat 49. The auxiliary frame element 38 with its parts may now be secured to the movable frame by the screws 39. The driving belt 76 which is elastic is put in place and the guard element secured to the movable base. Due to the relative simplicity in assembly of the guard element to the movable frame, access to the moving parts for purposes of lubrication and inspection is a simple matter, thus permitting longer trouble-free operation. The set screw 93 may now be inserted and the locking collar 9 and adjusting wheel 95 secured in place. The chuck is screwed to the main shaft 17 with the collet 92 in a cone shaped socket in the end 58, and the mixing element shaft 18 with the mixing element 19 may be secured in place.

Operation

The device is clamped to a suitable mixing vessel containing the materials to be mixed. The motor drive shaft 53 rotates in a counterclockwise direction when viewed from above. By means of the pulleys 54 and 75, and driving belt 76, the conical driving member 67 rotates counterclockwise, in turn driving the main shaft 17 in a clockwise direction. This clockwise direction of the main shaft retards loosening of the chuck 16, insuring non-slipping of the mixing element. Declutching or the disengagement of the conical driving member 67 from the member 84 is accomplished by turning the adjusting means 20 in a clockwise direction until there is a clearance between the conical driving member and the sliding member. This permits halting the mixing without opening the electrical circuit to the motor, thereby avoiding sparks. Regulation of the R. P. M. of the main shaft, which is of prime importance in the mixing process, is accomplished in a relatively convenient and easy manner. The locking collar 94 is loosened and the adjusting knob 95 turned until the desired R. P. M. is obtained. The fork member 86, being threadedly engaged with the adjusting screw 87, moves downwardly and upwardly, depending upon the direction in which the adjusting knob is rotated. Obviously, the lower the sliding collar is in relation to its contact point on the conical driving means 67, the slower the R. P. M. of the main shaft 17.

The changing of the effective length of shaft 18 or the substitution of another shaft is readily accomplished by manipulation of the means 16. The collar 91 and the locking collar 9 are rotated as a unit, while the collar 90 is held fixed, and the flange 85 is moved longitudinally of the shaft 17 in either direction to engage or disengage the chuck 16.

Turning now to the second embodiment of the invention, illustrated in Fig. 5, for the purpose of avoiding needless repetition, certain of the parts are given the same reference characters as those of the first embodiment with the addition of the prefix 1.

The device, generally indicated by reference character 110 comprises broadly a relatively stationary frame 111, a relatively movable frame 112, a prime mover 113, speed changing and power transmission means 114, a main shaft 117, declutching means 120, a mixing element shaft 118, a mixing element 119 and a support member 225.

The declutching means 120 comprises an externally threaded barrel 206 having a knurled adjusting knob 208 at one end thereof. Disposed within the barrel 206 is a helical spring 210, being connected at both ends thereof to the end caps 212 and 214.

The relatively movable frame 112 comprises a top wall 161 having an upstanding portion 222 and is provided with an orifice 223, a front wall 163, a rear edge 181 and a bottom portion 143. Extending rearwardly from the bottom portion 143 is an ear 197, penetrated by the pin 128. A countersunk bore 199 has been provided in the bottom portion 143 for passage of the main shaft 117 and an orifice 223 in the top wall for the bearing 144. A boss 227 extending upwardly from the top surface 240 of the bottom portion 143 has a bearing seat 249 therein to receive the lower end of the adjusting screw 187.

The relatively stationary frame 111 comprises a front edge 198, a rear wall 190 and a bottom flange 188. Disposed on the forward portion of

the bottom flange 188 is an ear 196 and rearwardly projecting from the bottom flange 188 is an ear 183. An internally threaded orifice 215 is provided in the upper portion 230 of the rear wall 190 to receive the barrel 206.

The support member 225 may be pivotally and adjustably connected to the ear 183 by a bolt and wing nut 250 and may be carried by any suitable adjustable stand (not shown) having a laterally extending arm 220.

The main shaft 117, having a central bore 215, is provided with externally reduced portions 216 and 217 at the ends thereof. The lower end of the shaft has external threads and is provided with a countersunk bore 218. Disposed longitudinally upon the axis of the main shaft are the keyways 155 which coat with keys (not shown) on the annular driven member 184.

The speed changing and power transmission means, generally indicated by reference character 114, comprises a conical driving member 167, the annular driven member 184 having an annular groove 220, a fork member 186 with arms 224.

The mixing element shaft holding means 116 may be identical with the form shown and described in the first embodiment of the invention.

Operation

In operation the second embodiment of the invention deviates from the first embodiment.

Declutching is obtained by turning the barrel 206 until the front end of the barrel contacts the portion 222 of the movable frame and forces the movable frame outward about the pivot 128. Only a slight movement is required to disengage the annular collar 184 from the conical driving member 167. The helical spring 210 within the barrel 206 insures adequate frictional engagement between the driven annular member 184 and the driving member 167, and tends to prevent slipping of the member 184 when liquids of a high viscosity are being mixed.

To assemble the second embodiment of the invention, the movable frame with its members, and the stationary frame are each assembled separately and then joined by means of the pin 128 and the declutching means 120.

To assemble the movable frame 112, the adjusting screw is engaged with the fork member 186 and held in place by the set screw 193. The main shaft 117 may now be passed through the orifice 223 in the top wall 161 engaging the annular collar 184 and coming to its operating position when the enlarged portion of the shaft 117 contacts the bearing 147. The bearing 144 may now be forced into position and the locking disc 260 made secure to the movable frame 112 by means of the screws 252. The chuck means 116 and the collar 190 may be placed upon the shaft 117 at this time and the mixing element shaft 118, with the mixing element 119, can then be inserted into place.

The stationary frame 111 may be assembled by mounting the motor 113 on the bottom flange 188 and securing the driving member 167 to the motor shaft. The barrel 206 of the declutching means may now be screwed into place. At this time the stationary frame and movable frame may be joined by means of the pivot pin 128 and the spring 210 inserted within the barrel 206 of the declutching means 120 and retained in place by the end caps 212 and 214. The spring 210 is hooked on to the caps 212 and 214.

I wish it to be understood that I do not desire to be limited to the exact details of construction

shown and described, for obvious modifications will occur to a person skilled in the art.

I claim:

1. A mixer comprising: a first frame; a second frame; said first and second frames being pivotally interconnected; a main shaft journaled in the second frame and having an impeller at one terminus thereof; a collar; said collar being reciprocably slideable along said shaft, and being keyed to said shaft; a collar engaging member; a screw threadedly engaged by said collar engaging member; said collar engaging member being reciprocably movable, along said screw by rotation of said screw; a cone rotatably mounted on the first frame and engaging said collar; and declutching means; said declutching means acting to separate the cone from the collar; the axis of said cone and main shaft having a non-parallel relationship with respect to each other; said declutching means maintaining said cone and said collar in engagement by first resilient means, and having a second positive means for separating said cone and said collar against said first mentioned resilient means.

2. A mixer comprising: a first frame; a second frame; said first and second frames being rotatably interconnected; a main shaft journaled in the second frame, said main shaft having a keyway; said keyway being arranged axially in said shaft; a collar; said collar having a key and being reciprocably slideable along said shaft; a collar engaging member; a screw threadedly engaged by said collar engaging member; said collar engaging member being reciprocably movable along said screw by rotation of said screw; a cone rotatably mounted on said first frame and engaging said collar; the axes of said cone and said main shaft being disposed at an angle with respect to each other; and declutching means; said declutching means serving to rotate said first frame with respect to said second frame, whereby said cone is disengaged from said collar; said declutching means including a spring for maintaining said cone and said collar in resilient engagement, and a shaft threadedly engaged upon said first frame and bearing against said second frame, rotation of which serves to separate said collar and said cone against the resilient action of said spring.

3. A mixer comprising: a first frame; a second frame; said first and second frames being pivotally interconnected; a main shaft journaled in the second frame and having an impeller at one terminus thereof; a collar; said collar being reciprocably slideable along said shaft, and being keyed to said shaft; a collar engaging member; a screw threadedly engaged by said collar engaging member; said collar engaging member being reciprocably movable along said screw by rotation of said screw; a cone rotatably mounted in a shaft bearing on the second frame and resiliently engaging said collar; said shaft bearing in turn being pivotally mounted for rotation about an axis perpendicular to the axis of said cone; resilient belt drive means engaging a pulley driving said cone, said pulley and said cone being on opposite sides of the pivotal mounting of said shaft bearing; said belt tending to resiliently urge said shaft bearing in a first direction of rotation, whereby said cone may resiliently contact said collar; means for adjusting the position of said shaft bearing about said pivotal mounting, said means serving to positively urge the shaft bearing in a second direction of rotation opposite said first mentioned direction of

rotation against the resilient action of said belt, whereby said cone may become disengaged from said collar.

ABRAM I. PODELL.
